(57) **CLAIM**

The ornamental design for a parking lot sign, as shown and described.

DESCRIPTION

FIG. 1 is a perspective view of the first embodiment of a parking lot sign shown in an environment of use, showing our new design;

FIG. 2 is a top view thereof;

FIG. 3 is a left-side view thereof, the right-side being mirror image thereof;

FIG. 4 is a front view thereof, the rear view being a mirror image thereof;

FIG. 5 is a perspective view of the second embodiment of a parking lot sign shown in an environment of use;

FIG. 6 is a top view thereof;

FIG. 7 is a left-side view thereof, the right-side view being a mirror image thereof; and,

FIG. 8 is a front view thereof, the rear view being a mirror image thereof.

The broken line portion of the figure drawings is included to show environment that form no part of the claimed design.
